ATTORNEYS.

UNITED STATES PATENT OFFICE.

ROBERT T. WALTON, OF PHILADELPHIA, PENNSYLVANIA.

ROTATABLE FLAG SUPPORT.

Application filed July 2, 1926. Serial No. 120,074.

My invention relates to a new and useful flag support, whereby a flag staff or the like may be firmly and detachably supported in an upright position, on side walks, 5 pavements and the like, when it is desired to decorate the streets on festival and other occasions of a public or national character, and in addition the flag proper is carried by the flag staff in a rotatable manner so that 10 the same may turn around with the wind, and stand at all times unfurled, thus maintaining the flag or emblem completely unfurled or in a vertical plane at all times and preventing the same from becoming 15 wrapped or otherwise entangled around the flag staff.

A further object of my invention is to provide a flag support which may be placed in position and removed with a minimum 20 of time and effort and which at the same time is stable, durable and ornamental.

With the above ends in view my invention consists of a flag staff, a collar carried by and rigidly secured to said flag staff at 25 a suitable point above the lower extremity thereof, a sleeve rotatably mounted on the upper portion of said flag staff and means to clamp the inner edge of a flag or emblem in vertically disposed flanges of said sleeve, 30 the latter being prevented from longitudinal movement.

For the purpose of illustrating my invention I have shown in the accompanying drawing several forms thereof which are at 35 present preferred by me, since the same have been found in practice to give satisfactory and reliable results, although it is to be understood that the various instrumentalities of which my invention consists 40 can be variously arranged and organized and that my invention is not limited to the precise arrangement and organization of the instrumentalities as herein shown and described.

Figure 1, represents a front elevation of a rotatable flag support, embodying my invention.

Figure 2, represents a vertical section on line 2—2 of Figure 1.

Figure 3, represents a transverse section on line 3—3 of Figure 1.

Figure 4, represents a side elevation of the upper portion of the flag staff.

Figure 5, represents a bottom plan view 55 of the flag staff.

Figure 6, represents a side elevation of a modification.

Referring to the drawings in which like reference characters indicate like parts.

1 designates my novel construction of a flag support, the same comprising the flag staff 2 which can be hollow or solid, having the lower terminal 3, which is rotatably seated or fitted in the sleeve 4, which is embedded in the pavement 5, the top of said sleeve being flush with the top of the pavement. The lower end of the terminal member 3 is serrated or provided with V shaped cuts 6, which enable the lower end 3 upon being rotated to bore its way into the sleeve 4 in case the latter becomes filled with dirt or the like. 7 designates a collar which is fast on the staff 2 and which limits the downward movement of the staff with respect to the pavement, said collar being sufficiently wide to assist in retaining the staff and flag in an upright or vertical position. 8 designates the flag or emblem whose inner edge 9 is clamped between the parallel flanges 10 of the sleeve 11, which is rotatably mounted on the upper portion of the staff 2 and which is prevented from longitudinal movement thereon by the transverse pin 12, which is retained between the walls of the groove 13 at the upper end of said staff. The flanges 10 are co-extensive with the height of the flag or emblem 8, and the edge 9 thereof is clamped firmly between said flanges by the screws, bolts or other fastening devices 14.

In the construction seen in Fig. 6 the sleeve 11 is prevented from longitudinal displacement by the collar 15 which may be fast to the staff 2 or supported thereon by the pin 16.

The sleeve 11 as shown in Figs. 1 and 2 terminates at its upper end in the cap or closure 17, which may be of any desired shape or configuration, and which may be formed integrally with said sleeve, and serves not only as an ornamental finish to the top of said sleeve, but also as a closure for said sleeve preventing the egress of rain or moisture thereinto. In the construction seen in Fig. 6 the top of the staff 2 may be provided with a collar 18 of the contour shown, which in conjunction to the lower collar 15 serves to retain the sleeve 11 seen in Fig. 6 and to prevent longitudinal movement thereof on the flag staff.

It will be understood that in all the embodiments of my invention, the sleeve 11 and the flag 8 carried thereby are rotatable as a unit upon the staff 2 and since the inner edge 9 of the flag or emblem 8 is secured for its entire height within the flanges 10, the flag will tend to stand at all times unfurled or in a substantially vertical plane and in whichever direction the wind may be blowing the flag 8 and the sleeve 11 can be freely rotated on the shaft 2. The grooved bottom end 6 of the flag staff enables the lower terminal 3 thereof when turned in the manner of an auger, to bore its way into the sleeve 4 in case the same is filled with dirt or the like. In the construction seen in Figs. 1 and 2 it will be apparent that since the transverse pin 12 is confined between the walls of the slot 13, that the flag 8, sleeve 11 and its adjuncts will be at all times prevented from longitudinal movement with respect to the flag staff and are enabled to rotate

freely at all times according to whatever direction the wind may be blowing. The collar 7 serves to maintain the flag staff in a substantially vertical or upright position within its sleeve or seat 4 at all times as is evident.

Having thus described my invention what I claim as new and desire to secure by Letters Patent, is:—

In a device of the character stated, a flag staff, an elongated sleeve extending longitudinally of, and surrounding the upper end of said flag staff and freely rotatable thereon and provided with parallel vertical flanges, a flag having its inner edge clamped between said vertical flanges, and means comprising a pin in said sleeve engaging a groove in said flag staff for preventing longitudinal shifting of said sleeve and flag with respect to said flag staff.

ROBERT T. WALTON.
